George W. Yates

By his Attorneys

Edgar Yates & Co.

UNITED STATES PATENT OFFICE.

GEORGE W. YATES, OF WEST HOBOKEN, NEW JERSEY.

DESIGN FOR A COIN-RECEIVER.

53,954.

Specification for Design.

Patented Oct. 7, 1919.

Application filed May 8, 1919. Serial No. 295,788. Term of patent 3½ years.

To all whom it may concern:

Be it known that I, GEORGE W. YATES, a citizen of the United States, and residing in West Hoboken, in the county of Hudson and State of New Jersey, have invented a new, original, and ornamental Design for a Coin-Receiver, of which the following is a specification, reference being had to the accompanying drawing, forming part thereof.

The figure is a perspective view of a coin receiver, showing my new design.

I claim:—

The ornamental design for a coin receiver, as shown.

GEORGE W. YATES.

Witnesses:

C. E. MULREANY,
H. E. THOMPSON.
